UNITED STATES PATENT OFFICE.

FRIEDRICH OTTO ZIMMERHAECKEL, OF NEW YORK, N. Y.

BOOK-COVER PROTECTOR.

1,264,252.

Specification of Letters Patent. Patented Apr. 30, 1918.

Application filed April 23, 1915. Serial No. 23,439.

To all whom it may concern:

Be it known that I, FRIEDRICH OTTO ZIMMERHAECKEL, a subject of the German Emperor, residing at New York, in the county of New York and State of New York, have invented certain new and useful Improvements in Book-Cover Protectors, of which the following is a specification.

My invention relates to book cover protectors.

The primary object of my invention is to provide a book cover protector capable of detachable disposition on a book to protect the same against dirt, dust, or the like, which is simple in construction, cheap to manufacture, and quickly and easily secured on a book.

Another object of my invention is to provide a book cover protector of the above described class which is capable of use in connection with books of varying sizes, means being associated therewith for embracing the cover of a book to prevent casual displacement of the cover protector.

A still further object of my invention is to provide a book cover protector constructed of a sheet of inexpensive material formed with suitable means for preventing dislodgment of the same from a book.

With the above and other objects in view my invention resides in the construction, combination, and arrangement of parts as hereinafter set forth in the specification and illustrated in the accompanying drawings, in which—

Figure 1 is a plan view of my improved book cover partly in section, showing the same applied to a book.

Fig. 2 is a fragmentary plan view of the blank from which my improved book cover is formed.

Fig. 3 is a transverse sectional view of the book cover protector taken on the line 3—3 of Fig. 1, and looking in the direction of the arrow.

Fig. 4 is a plan view of the blank from which the retaining strap is formed.

Fig. 5 is a fragmentary plan view of another form of my invention.

Fig. 6 is a transverse sectional view taken on the line 6—6 of Fig. 5 and looking in the direction of the arrow.

Fig. 7 is a fragmentary plan view of the blank from which the form of my invention illustrated in Fig. 5 is made.

Fig. 8 is a longitudinal sectional view taken on the line 8—8 of Fig. 5, and

Fig. 9 is a detail view of a portion of the bottom edge of a book showing the cover applied.

Similar reference characters indicate similar parts throughout the various views of the drawings.

One form of my invention is illustrated in Figs. 1 to 3 inclusive. In this form of my invention a blank of suitable material, such as light paper, cardboard or the like, is provided and has arranged thereon creases, in this instance, three in number, the blank sheet of material being indicated by the numeral 1 and the creases by the numeral 2. The creases 2 are disposed substantially intermediate the length of the blank and the same is reversely folded on said creases to provide a pair of spaced portions 3 and 4 for a purpose which will hereinafter appear. The blank 1 is provided on its longitudinal marginal edges with tongues 5, one only being shown in Fig. 2, a crease 6 being provided adjacent the point at which the tongue joins the blank 1 in order to facilitate folding of the same in the manner hereinafter set forth. The several lateral marginal edges of the blank 1 are folded, preferably three times upon themselves, suitable creases 7, 8 and 9 being provided for this purpose, portions 10, 11, and 12 of the blank 1 being foldable as illustrated in Fig. 3 to provide a pocket 13 for a purpose which will hereinafter be set forth, it being noted that the portion 10 is first folded upon the crease 7, the portion 11 being in turn folded upon the crease 8 reversely to the portion 10 and in parallelism thereto, the tongue 5, of which there are two in the completed article, being receivable between the portions 10 and 11. The portion 12 is now bent beneath the blank 1, a suitable adhesive material,

such as mucilage or the like is provided for permanently securing the tongues 5 and portions 10, 11 and 12 in the manner shown in Fig. 3. This process provides a pocket or recess 13, hereinbefore referred to which is adapted to receive the outer marginal edge of one cover of the book designated 14 in Fig. 1. Additional means is provided for engagement with a book cover, this means comprising a strap 15, the opposite extremities 16 of which are receivable between the portions 3 and 4, folded as hereinbefore set forth, the manner in which the extremities 16 are receivable between the folds 3 and 4 being shown to advantage in Fig. 3.

In disposing the book in position, one side of the cover of the book is receivable under the strap 15, this cover being designated 17 in Fig. 1, the leaves of the book being designated 18. The other side of the cover, namely 14, is receivable in the pocket 13. It will thus be seen that the leaves of the book form an abutment against which the strap 15 engages and movement of the protector relative to the book cover is practically impossible in this direction. In order to prevent casual displacement of the cover protector, the free marginal edges of the cover 14 are receivable in the pocket 13 in the manner hereinbefore set forth, and it will be noted that movement in any direction of the protector is practically impossible without intentional removal of the cover protector.

35 In Figs. 5, 6, 7, and 8, I have illustrated a modified form of my invention. In this form of my invention I provide a blank 19, said blank being folded on the creases 20 and 21 to provide transversely extending folded portions 22 and 23, respectively, the said portion 22 having two parallel portions 24 and 25 between which are receivable the opposite extremities 27 of a retaining strap or band 26, substantially identical to the construction shown in Fig. 3 for retaining the strap 15 in position. The object of the folded portion 23 is to provide a clamping or retaining abutment and its advantage will readily become apparent hereinafter.

50 A further retaining band 28 is provided, the opposite extremities 29 thereof being bent into parallelism with the main portion of the strap 28 and engageable between the portions of the blank 19 where the same is reversely folded as indicated at the point 30. The blank 19 is additionally creased at the point 31 co-extensive with the outer marginal edge of the folded portion 23 for a purpose which will hereinafter become apparent.

In applying this form of my cover to a book the back of the book is receivable between abutments 22 and 23, one-half cover of the book being first inserted beneath the

strap 26. The other half cover of the book 65 is now receivable beneath the strap 28 and assuming that the book is of a thickness co-extensive with that of the portion of the blank between the abutments 22 and 23, the protector will be effectively retained on the 70 book. Should the book be of a greater thickness than the distance between the abutments 22 and 23, the abutment 23 may be folded into parallelism with the blank 19 and the cover protector folded on the crease 75 31. It has been found practicable, however, to manufacture these covers in different sizes to be employed with the size of book best adapted to the same and provision of the abutments 22 and 23 affords gripping and 80 retaining means, being assisted by retaining straps 26 and 28. I desire to lay particular stress upon the manner in which the retaining straps of both forms of my invention are associated with the book cover protector, as 85 well as the construction embodied, the peculiar manner in which the same is applied to a book not necessarily effecting the patentability of the various forms of my invention. Further attention is directed to the gripping 90 and retaining abutments 22 and 23. It is, of course, to be understood that the straps 26 and 28, folded portions 24 and 25, the abutment 23, and the folded portion 30 are to be all secured with some adhesive mate- 95 rial, such as mucilage or the like.

It is desired that it be understood that while I have shown my invention applied and used as a book cover protector, it will be readily understood that the same might 100 be illustrated for retaining photographs, postal cards and the like, this being the case particularly in the form of my invention illustrated in Figs. 1 to 4.

While I have shown and described my invention as possessing a peculiar form and construction, it is desired that it be understood that I may make such changes in the details thereof that do not depart from the spirit and scope of the invention as claimed. 105

Having thus described my invention, what I claim and desire to secure by Letters Patent is:

1. A book cover protector, including a body portion, said body portion being folded 115 upon itself intermediate of its ends to provide an abutment for engagement with one side of a book binding, means included in the folded portion adapted to encircle the book cover adjacent to the binding whereby 120 the protector is retained on the book cover, and pockets arranged upon the lateral marginal edges of the body portion of the protector for receiving the ends of the book cover.

2. A book cover protector including a body portion folded upon itself intermediate of its ends to provide a pocket and an

abutment for engaging one side of a book binding, a strap adapted to lie in the pocket and encircle the adjacent portion of a book cover, tongues arranged upon the longitudinal marginal edges of the body portion, pockets formed upon the lateral marginal edges of the body portion adjacent to the tongues by folding said lateral marginal edges upon themselves and folding and se-

curing the tongues between the folds of the 10 pockets.

In testimony whereof I affix my signature in presence of two witnesses.

FRIEDRICH OTTO ZIMMERHAECKEL.
